UNITED STATES PATENT OFFICE

163,334

BELT BUCKLE

Lonnie Lee Shores, Los Angeles, Calif.

Application July 26, 1949, Serial No. 4,139

Term of patent 3½ years

(Cl. D17—1)

To all whom it may concern:

Be it known that I, Lonnie Lee Shores, a citizen of the United States, residing in Los Angeles, in the county of Los Angeles and State of California, have invented a new, original, and ornamental Design for a Belt Buckle, of which the following is a specification, reference being had to the accompanying drawing, forming part thereof.

Fig. 1 is a front elevational view of a belt buckle, showing my new design.

Fig. 2 is a cross-sectional view as taken on line 2—2 of Fig. 1, and looking in the direction of the arrows.

Fig. 3 is a top plan view.

The dominant features of the design reside in the portions shown in full lines.

I claim:

The ornamental design for a belt buckle, substantially as shown and described.

LONNIE LEE SHORES.
